CLAIM

The ornamental design for a protective eye wear shield or the like, as shown and described.

DESCRIPTION

FIG. 1 is a front perspective view of a protective eye wear shield or the like showing my new design;
FIG. 2 is a front elevational view thereof;
FIG. 3 is a rear elevational view thereof;
FIG. 4 is a top plan view thereof;
FIG. 5 is a bottom plan view thereof; and
FIG. 6 is a left side elevational view, the right side being a mirror image thereof.

FIG. 4**FIG. 1****FIG. 5****FIG. 6****FIG. 2**

FIG. 3
